FOREIGN PATENT DOCUMENTS

CN 102011904 A 4/2011

Primary Examiner — Eric Goodman*Assistant Examiner* — Amy Wierenga(74) *Attorney, Agent, or Firm* — Ware, Fressola, Maguire & Barber LLP(57) **CLAIM**

The ornamental design for a raintight fitting connector body, as shown and described.

DESCRIPTION

FIG. 1 is a front perspective view of the raintight fitting connector body of my design;

FIG. 2 is a right side view thereof;

FIG. 3 is left side view thereof;

FIG. 4 is top view thereof;

FIG. 5 is a bottom view thereof;

FIG. 6 is a front view thereof;

FIG. 7 is a rear view thereof; and,

FIG. 8 is an elevational view of FIG. 2 shown in a position of use.

The dashed lines shown in FIG. 7 depict portions of the article that form no part of the claim. The dashed lines shown in FIG. 8 depict environmental subject matter that forms no part of the claim.
